UNITED STATES PATENT OFFICE.

EDWIN J. RILEY, OF LA CYGNE, KANSAS.

AUTOMATIC AIR-VALVE.

1,292,062.

Specification of Letters Patent. Patented Jan. 21, 1919.

Application filed May 3, 1916, Serial No. 95,064. Renewed June 13, 1918. Serial No. 239,892.

To all whom it may concern:

Be it known that I, EDWIN J. RILEY, a citizen of the United States, residing at La Cygne, in the county of Linn and State 5 of Kansas, have invented certain useful Improvements in Automatic Air-Valves, of which the following is a specification, reference being had therein to the accompanying drawing.

- 10 This invention relates to improvements in automatic air controlling valves for explosive engines, and more particularly for the engines used upon motor cars, one object of the invention being the provision of a 15 valve adapted to be connected at the fork of the intake manifold, whereby during the pulsation of the engine, the air is directed to the manifold at a point between the carbureter and the intake port of the engine.
- 20 A further object of the present invention is the provision of an air inlet valve which is simple and durable in construction and which is readily placed in position for use.

In the accompanying drawings:—

- 25 Figure 1 is a diagrammatic view of an explosive engine showing the carbureter and intake manifold equipped with the present valve.

Fig. 2 is a longitudinal sectional view 30 through the valve.

Figs. 3 and 4 are detailed views of parts of the valve.

Fig. 5 is a top plan view of the device.

Referring to the drawings, the numeral 5 35 designates the carbureter and 6 the manifold, the present air valve 7 being attached in a port 8 of the manifold at a point between the intake of the engine 9' and the carbureter.

40 This valve comprises a casing 9 having its main bore enlarged as at 11, the enlarged end of said casing being provided with the threaded portion 12, the valve seat 13 and the air inlet ports 14.

45 A valve stem 15 is adapted to project through the bore of the casing 9 and carries upon its inner end the valve 16 which normally is seated upon the seat 13. The outer end of the stem 15 is threaded as at

17 and extends beyond the casing 9 to receive the adjusting nut 18 and the lock nut 19, a coil spring 20 being disposed externally of the reduced end 21 of the casing 9 and abutting respectively the annular shoulder 22 thereof and the adjusting nut 18. 50

By this means the spring 20 normally holds the valve 16 seated and in such a manner that the spring may be adjusted at any desired tension according to the requirements of the engine. It will be noticed that a bracket 23 is secured upon the outer end of the valve casing and extending outwardly therefrom is a pin. Fulcrumed upon this pin is a segmental or sector shaped plate 25 serving as a cam and adapted, when 60 it is turned, to have its curved edge wedged against the knurled adjusting nut 18 of the valve stem so as to be locked in frictional engagement with the same. There is an actuating rod 40 pivotally secured to the 65 plate 25 by means of which the plate can be turned upon the pivot 24 into and out of locked frictional relationship with the head of the valve stem.

This valve lock is operably connected to 70 the throttle, not shown, so that the same may be readily operated from the seat of the motor car.

From the foregoing description taken in connection with the drawings, it is evident 80 that with a device of this character, a better mixture of air with the explosive charge after passing through the carbureter is provided, and also that with the present device the admission of air may be regulated to 85 an exactness and in proportion to the power of the engine.

What I claim as new is:—

In a device of the class described, in combination, a valve casing, a support therefor, 90 said casing at its inner end having a valve seat, a valve stem in said casing having a valve shaped to fit said seat, said valve stem having a threaded portion projecting beyond said casing, a knurled adjusting nut 18 95 mounted upon the threaded projecting portion of said valve stem, a spring of lesser diameter than said adjusting nut engaging

the latter as well as the outer end of said casing, a bracket secured to said casing, an outwardly projecting pin formed on said bracket, a segmental plate fulcrumed on said 5 pin and adapted to have its curved edge engaged against the peripheral margin of the inner side of said adjusting nut so as

to hold said adjusting nut locked against movement to compress said spring, and an operating arm for turning said segmental 10 plate upon its pivot to locked or released position.

In testimony whereof I affix my signature.

EDWIN J. RILEY.
